CRANE

Howard J. King, Wilkinsburg, and George A. Jacobi, Moon Township, Allegheny County, Pa., assignors to Dravo Corporation, Pittsburgh, Pa., a corporation of Pennsylvania

Application October 27, 1944, Serial No. 560,576

12 Claims. (Cl. 212—3)

1

This invention relates to material handling equipment of the type in which there is a swinging boom or jib, and relates particularly to a boom or jib construction by which raising and lowering of the jib into or from an operating position may be effected.

In apparatus of this type, and specifically in cranes and derricks mounted on boats or barges, it is desirable to lower the crane below its maximum reach, or lowermost operating position, either for lashing the jib down so that it cannot whip or move about when the boat or barge is being moved from one position to another, or so that it will clear bridges or other structures. Also in apparatus of this kind, whether the derrick or crane be on a barge or be on land, it is desirable to lower the boom or jib below its lower normal limit of movement for storage or repairs.

In conventional cranes of this type, it is the practice to extend the operating mechanism through which the jib is raised or lowered, so as to allow for the full desired range of movement of the jib even to the lowered or storing position. This, particularly in large, heavy cranes, increases considerably the cost of the operating mechanism, the weight of the mechanism, and may create an inconvenient geometrical arrangement in the design of the crane. Normally, in use, the boom or jib is swung from its position of minimum reach, i. e., where it is most nearly vertical, to its position of maximum reach, i. e., in the operating position at which it is most nearly horizontal. This is usually an arc of somewhat less than 90°. To lower or drop the jib several degrees below its position of maximum reach at the present time requires that the operating mechanism be capable of swinging the boom or jib not only through its normal operating range, but also an additional distance whereby the overall movement may be through an arc in excess of 90°. This operating mechanism is heavy, cumbersome, and expensive, and since the portion which permits the extended range of movement is only used at such occasional times as the boom is being lowered into position for storing or repairs, or raised from such a lowered position, a considerable increased mass of expensive machinery is thus provided for transient and momentary situations.

According to the present invention, there is provided an arrangement in which the mechanism for raising and lowering the boom will have an operating range only sufficient to move the boom or jib in the range between its positions of maximum and minimum reach. To lower the

5 jib to a position for storage or repairs, our invention provides a hinge structure or section in the jib adjacent the base operably interposed between the main portion of the jib and the operating mechanism with a releasable and extensible connection which can be utilized in effecting an auxiliary movement of the jib from its position of maximum reach to a lowered position for storage and repairs. The hinge in the jib or boom structure is normally inactive, because of the presence of a rigid linkage that prevents relative movement between the hinged portions, and the jib thus normally functions as a completely rigid boom. However, when it is to be lowered beyond its operating range, provision is made for independently supporting the main portion of the jib while the releasable linkage is disconnected and the inner part of the jib is separately moved by the jib operating mechanism 10 relative to the main section of the jib, and thus change the angular relation between the two sections. As this relative movement of the two parts of the jib takes place, an extensible linkage comes 15 into operation, coupling the sections in their new relation. Then by again operating the jib operating mechanism in a direction to lower the jib, the jib as a whole will move, and the outer portion of the jib will lower from the position of maximum reach to a position for storing and repairing the jib. Thus while the operating mechanism is capable of moving the jib through 20 an arc somewhat less than 90°, the hinge arrangement permitting a change in the angular relation of the two parts of the jib enables the jib to be effectively moved through a much greater arc.

25 Our invention therefore reduces considerably the cost of the operating mechanism, its weight, and simplifies the problems of design, while the hinge in the boom is a negligible item in over-all cost of the crane.

30 Our invention may be more fully understood by reference to the accompanying drawings, in which:

35 Fig. 1 is a more or less conventional illustration of a crane of the type to which the present invention relates, showing in full lines the position of the boom or jib at maximum reach, the dot-and-dash lines showing the position of the jib when it is at a position of minimum reach, and the dotted lines showing the jib lowered for storage;

40 Fig. 2 is a front elevation of the construction shown in Fig. 1;

45 Fig. 3 is a fragmentary view on a larger scale

showing in greater detail, but still more or less schematically, the construction at the base of the jib and the operating mechanism;

Fig. 4 is a line drawing showing the jib in the position of minimum reach;

Fig. 5 is a similar view showing the jib in the position of maximum reach;

Fig. 6 is a view similar to Fig. 5, showing the first step toward lowering the jib beyond the position of maximum reach to a storage position, with the cable attached to the movable outer section;

Fig. 7 is a similar view in which the jib has been again lowered to bring special cables which are at this time brought into play, taut;

Figs. 8 and 9 are detailed views of the upper part of the hinged portion of the jib with the cables in position, Fig. 8 showing the wedge blocks still in place between the two sections of the jib, and the temporary linkage in position, whereas in Fig. 9 the wedge blocks are removed and the said links are disconnected;

Fig. 10 is a schematic view showing the equalizer through which the temporary cables are connected, the view being generally a schematic view;

Fig. 11 shows a succeeding step in which the extensible linkage between the hinged parts of the jib has come into play, and the jib has been raised slightly to slacken the tension on the temporary cables; and

Fig. 12 shows the jib lowered to a position for storage or repairs, the temporary cables at this time having been disconnected.

In the drawings we have disclosed one particular type of crane with a screw type of operating mechanism for moving the jib through a vertical arc. It will be understood, however, that this is purely by way of illustration, and that the invention is applicable to various types of cranes, and with various types of operating mechanisms.

Referring now to the specific construction disclosed in the drawings, there is disclosed in Fig. 1 a support such as the boat or barge 2 on which is a platform 3 carrying a turret or turntable 4 on which is a super structure 5. Pivotedly mounted on the turntable, to move in a vertical arc, is a jib or boom designated generally as 6, and which has its pivotal support on the turntable at 7, the pivot point 7 as best shown in the schematic figures, as for example Fig. 4, being at the inner end of the boom which is of a generally triangular truss form.

The crane generally is of a more or less conventional construction, except for the features to be hereinafter described. Instead of the jib being a unitary member, as has heretofore been the common practice, the jib of the present invention may be considered as having two parts, comprising a main boom or jib portion 8, and an auxiliary or base portion 9, the base portion being pivotally hinged to the main portion at 10. The main portion 8 has an inner end frame structure 11, and the base portion 9 has a normally substantially parallel frame structure 12, the pivot 10 providing a pivoted connection between these two frame structures.

The base portion 9 has a second frame structure 13 which diverges from the frame structure 12, and as best shown in Fig. 3, the members 12 and 13 are connected at their upper and outer ends by a connecting structure 14, so that the inner auxiliary jib section 9 is of generally triangular form. The connecting portion 14, it will be perceived, forms in effect a continuation of

the upper chord of the truss-like structure of the jib portion 8.

The crane operating mechanism may be of any well known or preferred type. In the drawings, the operating mechanism is designated generally at 15. It comprises a rigid frame structure having its lower end pivotally mounted on the turntable at 16. It is provided with a longitudinally extending screw shaft 17 that is driven by a motor and reducing gear 18. A nut 19 is slideably and non-rotatably mounted in the frame 15, and this nut is provided with trunnions 20 which pivotally engage the frame member 14.

The motor 18, which is a reversible motor, serves to drive the screw shaft in either direction, and the turning of the screw shaft causes the nut 19 to move back and forth along the frame 15. This in turn raises and lowers the jib and the range of movement of the jib is limited to the length of travel of the nut 19 on the shaft 17. A mechanism of this general type is shown in Patent 2,188,686 of January 30, 1940.

In order that the two sections of the jib 8 and 9 will be rigidly connected in the normal operation of the crane, the frame structures 11 and 12 are normally coupled together by short links 21. These links are permanently mounted on pins 22 at the upper end of the frame structure 11 of the main jib section. They have slotted end portions 23 which loosely engage over pins 24 at the top of the frame structure 12 of the auxiliary jib section. These links normally connect the two portions 8 and 9 against relative movement about the hinge or pivot 10 so that when the nut 19 of the operating mechanism is moved back and forth, the whole jib moves as a rigid unit. Wedge blocks 27 may be placed between the two frame structures 11 and 12 during the normal operation of the crane to avoid any looseness in the linkage between the two parts of the jib.

In addition to the short links 21, there are folding or toggle links 25 which are pivoted to each other at 26, and which have their ends engaging the pins 22 and 24. These toggle links form an extensible linkage which can be opened out when the short links 21 are operated to uncouple the two sections of the jib, the toggle linkage then serving to limit the relative movement between the two sections of the jib, and to provide in effect an extension or elongation of the upper chord of the truss-like structure of jib portion 8, as may be understood upon considering Figs. 11 and 12.

Firmly anchored on the turntable, as best shown in Fig. 10, are two clevises designated 28. Each clevice 28 carries a bell crank 29. The parallel longitudinal arms of the two bell cranks are connected by a cross-linkage 30, and the other arms of each bell crank carry an equalizer 31. To each end of each equalizer is connected a fixed length of cable 32, and each of these cables, as best shown in Figs. 8 and 9, is provided with a clevice 33 at its outer end, which clevice is designed to be engaged over one of the pins 22. These cables are used in the manner hereinafter described, and the bell cranks and equalizers provide an equalizing system for equalizing the strain on the several cables.

In operation the crane normally swings from the minimum reach position, in which the jib is most nearly vertical, and which is shown in Fig. 4, to the maximum reach position in which the jib approaches most nearly a horizontal position. This movement of the jib between the maximum and minimum reaches is of course accomplished

by the operating mechanism including the screw 17 and the nut 19. As hereinbefore stated, the range of movement of the jib is limited by the distance which the nut 19 may travel on the threaded shaft 17. The range of movement permitted by the nut 19 is sufficient for all normal conditions of operation of the crane. However, as shown in dotted lines in Fig. 1, and as shown schematically in Fig. 12, it is desirable at times to lower the boom below the position of maximum reach shown in Fig. 5 to a position where it can be stored or transported. To move the jib to this position, the operator first operates the crane to bring the jib in the position of maximum reach shown in Fig. 5. It will be noted at this time that the nut 19 is at the extreme end of the screw 17, and that the jib cannot therefore be lowered any farther. Then the operator raises the boom a slight distance as shown in Fig. 6 and attaches the clevises 33 on the cables 32 to the pins 22. In Fig. 10 the several cables are indicated as being so attached to the pins. Then the boom is lowered again toward its position of maximum reach until the cables 32 become taut, as indicated in Fig. 7, and the links 21 are disengaged from the pins 24. As soon as this is done, the jib is held in the position of maximum operating reach by the cables 32, and the inner end section of the jib 9 is free to move about the hinge 10. The operating mechanism is then operated to move the inner end section 9 in the direction in which it normally would move to raise the crane toward the position of minimum reach, the nut 19 traveling down the screw 17 until the toggle levers 25 are opened straight out, as shown in Fig. 11, and movement in this condition is continued, whereupon the toggle levers, becoming straight, start to lift the outer end of the jib. When the outer end of the jib has been lifted slightly, the cables 32 will become slack, as shown in Fig. 11, and the cables can be disconnected from the pins 22.

Following the disconnection of the cables, the operating mechanism may then be reversed, causing the nut 19 to travel up the screw 17 and lower the boom to the position shown in Fig. 12.

It will thus be seen that by forming the jib in two sections hinged together in the manner indicated, the angular relation between the two sections of the jib can be changed, making it possible for an operating mechanism which is effective through a very limited arc of movement to effect the movement of the jib through an arc of 90° or more. Since the operation of lowering the boom or jib to the position shown in Fig. 12, or lifting it from this position usually takes place at infrequent intervals, the manipulation herein described is not one which has to be frequently performed, nor one which would involve serious delay.

In raising the jib back to an operating range of positions, the operations previously described are performed in reverse order. It might be noted that the operating mechanism comprising the screw and the nut is one that is well known in the art and forms no part of the present invention, and it might also be pointed out that there is a second nut 19' on the lower part of the screw, and the pivotal connection between the operating mechanism and the platform is effected through this nut so that the nuts 19 and 19' move toward and away from each other simultaneously.

While we have illustrated and described one specific embodiment of our invention, it will be understood that this is by way of illustration, and

that various changes and modifications are within the contemplation of our invention and under the scope of the following claims.

We claim:

- 5 1. In a crane of the type having a jib mounted for movement in a vertical arc and having an operating mechanism for moving the jib, the invention herein described comprising a connection interposed between the operating mechanism and the jib, which connection includes means for varying the angular relation between the jib and the operating mechanism, and means for temporarily supporting the jib when a change in such angular relation is being effected.
- 10 15. 2. In a crane of the type having a jib mounted for movement in a vertical arc and having an operating mechanism for moving the jib, the invention herein described comprising a connection interposed between the operating mechanism and the jib, which connection includes means for varying the angular relation between the jib and the operating mechanism, and means for temporarily supporting the jib when a change in such angular relation is being effected, said means comprising a plurality of cables detachably secured to the jib and connected to an anchorage through an equalizing system.
- 20 25. 3. Apparatus of the character described including in combination a main boom pivoted at its lower end, an auxiliary boom pivoted at its lower end at substantially the pivot point of the main boom, a detachable connection at the upper end of said auxiliary boom between said main boom and said auxiliary boom to enable relative movement of the auxiliary boom independent of the main boom when said detachable connection is removed, and power actuating means connected with said auxiliary boom whereby to selectively move either the entire boom structure including the main and auxiliary boom, or the auxiliary boom independent of the main boom.
- 30 35. 4. Apparatus as defined in claim 3 and including a temporary holding or stay means, interposed between the main boom and a fixed support, to hold the main boom in fixed position during any period of independent movement of said auxiliary boom.
- 40 45. 5. A boom construction for cranes and the like comprising a main boom section hingedly supported for movement in a vertical arc, an auxiliary boom structure of triangular formation pivotally secured to the inner end of the main boom section and movable in a vertical arc relative to the main boom section, detachable linkage normally holding the main boom section and auxiliary boom structure against relative movement, and an operating mechanism connected with the auxiliary boom structure.
- 50 55. 6. A boom construction having a pivotally mounted inner section, an operating mechanism positively geared to said section for swinging it in a vertical arc, a relatively long outer boom section normally extending rigidly outward from said inner section, and an extensible coupling between said boom sections providing for the angular adjustment of one section relatively to the other.
- 60 65. 7. A boom construction having an inner section pivotally mounted for swinging in a vertical arc, an operating mechanism connected to said inner section at a point spaced from the pivotal mounting thereof for swinging the section in said arc, a relatively long outer boom section normally extending rigidly outward from said inner section, and an extensible coupling between said
- 70 75. 75.

boom sections providing for the angular adjustment of one section relatively to the other.

8. A crane construction comprising a base and a boom mounted thereon, said boom comprising an inner boom section and an outer boom section severally mounted to swing in a vertical plane, operating means connected to the inner boom section for swinging it relatively to said base, and means for normally connecting said boom sections to swing as a unit under the effect of said operating means on said inner section, said connecting means being releasable to permit said operating means to swing said inner section relatively to said outer section.

9. A crane construction comprising a base and a boom mounted thereon, said boom comprising an inner boom section and an outer boom section severally mounted to swing in a vertical plane, operating means connected to the inner boom section for swinging it relatively to said base, and means for normally connecting said boom sections to swing as a unit under the effect of said operating means on said inner section, said connecting means being releasable to permit said operating means to swing said inner section relatively to said outer section, together with means for limiting the swing of the inner boom section relatively to the outer boom section.

10. A crane construction comprising a base and a boom mounted thereon, said boom comprising an inner boom section and an outer boom section severally mounted to swing in a vertical plane, operating means connected to the inner boom section for swinging it relatively to said base, means for normally connecting said boom sections to swing as a unit under the effect of said operating means on said inner section, said means being releasable to permit said operating means to swing said inner section relatively to said outer section, said outer boom section comprising a jib and said inner boom section comprising a frame structure hinged to the inner

end of said jib, and means effective between said frame structure and said jib for limiting the swing of said frame structure relatively to said jib.

5 11. A crane having a jib, an operating mechanism for the jib, an auxiliary jib section at the inner end of the jib and coupled to said operating mechanism for effecting the swing of the jib, a releasable coupling between the jib and the 10 auxiliary jib, and an extensible coupling effective between the jib and the auxiliary jib when the releasable coupling is removed.

12. A boom having a relatively long outer jib portion and an inner portion secured for angular movement relatively to said outer portion, an extensible coupling between said inner and outer portions, and a boom swinging mechanism connected to said inner portion.
